BY *A. C. Paul*
ATTORNEY

UNITED STATES PATENT OFFICE.

LUELLA STILWELL KINNARD, OF CHICAGO, ILLINOIS.

BUG.

1,213,656.

Specification of Letters Patent. Patented Jan. 23, 1917.

Application filed March 23, 1915. Serial No. 16,414.

To all whom it may concern:

Be it known that I, LUELLA STILWELL KINNARD, a citizen of the United States, residing at the city of Chicago, in the county of Cook and State of Illinois, have invented certain Improvements in Rugs, of which the following is a description, reference being had to the accompanying drawing and to the figures of reference marked thereon.

10 This invention relates to new and useful improvements in rugs designed for floor, table or furniture coverings, and more especially to articles of this character formed as knitted or crocheted fabrics.

15 An object of the invention is to provide an article of the above character in which a strong cord, or some suitable equivalent, may be located entirely within and concealed by the enchain'd loops forming the knitted or crocheted fabric, whereby, while said article is sufficiently pliable and flexible to serve the purposes of a rug, it will still have a large degree of firmness and will retain its shape under all circumstances, and both 25 sides of the fabric may be made alike, so that either side can be used uppermost.

In the drawings which show by way of illustration one embodiment of the invention, Figure 1 is a plan view of a rug embodying my invention, Fig. 2 is an enlarged detail, and Fig. 3 is a cross section.

The invention consists in a rug or floor covering formed by the enchaining of loops of strong thread or yarn, or other suitable material, laying these enchain'd loops alongside one another, and joining adjacent rows as they are formed.

20 In order that the rug may be firm and hold its shape I form each knitted or crocheted chain, or row of loops, around a strong pliable cord which is concealed by the loops of yarn or thread, and which, at the same time, causes the article to retain its shape while having sufficient flexibility to cause it to conform substantially to the surface of the floor or other object upon which it rests.

Referring more in detail to the drawing, the invention consists of a rug or floor covering formed of a series of chains, 2, consisting of interlocking or interlooping loops of yarn or thread forming a chain of loops in which each row is joined to the adjacent row by the interlooping or inter-

locking of the loops in one row with the 55 loops in the next adjacent row. I prefer to interlock the loops of one row with the next adjacent row in order to secure the chains together in forming the rug or floor covering. It will be obvious that the en- 60 chain'd loops of one row may be otherwise joined to the next adjacent row.

While I have referred to the chain of loops as a knitted or crocheted chain it will be understood that I do not limit myself to 65 any particular way of interlooping or interlocking the loops. The interlocked loops are formed about a pliable cord, 3, which preferably extends entirely through the rug from the center to the outer edge thereof. 70 The loops forming the chain completely cover and conceal the cord running therethrough so that said cord is not visible either from the upper or lower surfaces of the rug. Both surfaces of the rug are usually formed 75 alike and either surface may be used uppermost.

The thread or yarn of which the rug is formed may be of any desired color and by using different colors at different portions of the rug any desired design may be produced.

I do not limit myself to the details of the construction as the same may be varied within considerable limits without departing from my invention.

Having thus described my invention what I claim is:

1. A rug or floor covering of the class described, comprising a body portion formed 90 by a series of rows of knitted or crocheted chains, adjacent rows interlooping with one another and a pliable core located within and concealed by the loops of said chain whereby said rug will be flexible and will 95 retain a flat position when in use.

2. A rug or floor covering of the class described, comprising a body portion formed by a series of rows of knitted or crocheted chains, adjacent rows interlooping with one 100 another, and a pliable core located within and concealed by the loops of said chain whereby said rug will be flexible and will retain a flat position when in use, and both sides of said rug will be alike.

3. A rug or floor covering of the class described, comprising a body portion formed by a series of rows of knitted or crocheted

chains, adjacent rows interlooping with one another, and a pliable core, formed of a suitable cord, located within and concealed by the loops of said chain whereby said rug will be flexible and will retain a flat position when in use.

In witness whereof, I have hereunto set my hand this 23 day of February, 1915.

LUELLA STILWELL KINNARD.
